UNITED STATES PATENT OFFICE.

MICHAEL A. DONOVAN, OF RANDOLPH, MASSACHUSETTS.

SEWING-MACHINE.

SPECIFICATION forming part of Letters Patent No. 236,938, dated January 25, 1881.

Application filed December 22, 1873.

To all whom it may concern:

Be it known that I, MICHAEL A. DONOVAN, of Randolph, in the county of Norfolk and State of Massachusetts, have invented a new and useful Improvement in Sewing-Machines, of which the following is a full, clear, concise, and exact description, reference being had to the accompanying drawings, making a part hereof.

10 The main object of my invention is to secure the passage of the shuttle through the loop, especially in those machines in which a hooked needle and waxed thread are used; and my invention consists, mainly, in a novel combination of a shuttle and hooked needle, and in a novel construction of the shuttle, its race, and driver, my main purpose being to make a hooked-needle waxed-thread sewing-machine in which the shuttle is sure to enter the loop 15 of thread presented to it by the hooked needle, and to pass without undue strain through that loop, the main difficulty in using a shuttle with a hooked needle being to make it certain that the shuttle shall enter the loop, and 20 the main difficulty in using a shuttle with a waxed thread being to make it certain that the shuttle shall pass through the loop without undue strain.

25 The shuttle provided with side bearings and having its nose or point midway between those bearings, so that it will be supported by its race on both sides and have its point midway between the walls of the race, constitutes another important feature of my invention.

30 The shuttle-driver below described, adapted to be supported by and moved in the shuttle-race, is also new with me, in that it has arms extending from its main portion along both sides of the shuttle and overlapping the nose 35 of the shuttle, its main portion adapted to act on the butt of the shuttle and its arms adapted to act on each side of the shuttle-nose.

40 The distinguishing characteristic of my invention, however, consists in the combination of a shuttle and a hooked needle in such a way that the line of motion of the needle intersects the line of motion of the point of the shuttle. By this combination the point of the shuttle 45 is brought, when the shuttle moves forward, into the loop of the needle-thread with certainty, even when the machine is running at a

50 very high speed, and the hooked needle being below the shuttle, and the loop being securely held in the hook, there is no danger of the loop being displaced. This combination is wholly 55 new with me, so far as I know. So long as the hooked needle and shuttle are accurately adjusted to cause the line of motion of the one to intersect that of the other, the shuttle-point will enter the loop of the needle-thread with 60 certainty, even if the needle be small and the speed high.

55 In using waxed thread, which is sticky, it is very desirable to use a double race, one raceway on each side of the shuttle, and with the extremity of the V-shaped nose of the shuttle midway between the walls of the race. This also constitutes a portion of my invention of considerable practical value and importance, heretofore all shuttles known to me having been 65 arranged with the points close up to one wall of the race.

70 The other portions of my invention consist in various combinations of the parts above named with themselves and with other parts, 75 fully described below, all of which I have found it best to use in making a practically-working waxed - thread shuttle sewing - machine.

75 In the drawings, Figure 1 is a perspective view of a sewing-machine embodying my invention, the overhanging arm being removed. Fig. 2 is a detached view of all the mechanism for giving its up-and-down movement to the needle, with the exception of the shaft, the 80 shaft being removed, in order that the rest of the mechanism may be clearly seen. Fig. 3 is a view of the mechanism shown in Fig. 2, taken from the outside of the machine, part of the frame of the machine being broken away. Fig. 4 is a plan of the mechanism for controlling the movements of the needle. Fig. 5 is a plan showing the shuttle, shuttle-race, and 85 shuttle-driver. Fig. 6 is a longitudinal section through the middle of the shuttle and shuttle-race shown in Fig. 5. Figs. 7 and 8 are cross-sections of the shuttle and shuttle-race, Fig. 7 looking toward the nose of the shuttle, and Fig. 8 toward the butt. Fig. 9 is an under view of the parts shown in Fig. 90 5. Fig. 10 is a longitudinal section, showing the frame, the throat-plate, and portions of the 95 100

shuttle-race, the rest of the machine being broken away. Figs. 11 and 12 illustrate means for actuating the shuttle; and Figs. 13, 14, and 15, means for regulating the length of stitch. 5 Figs. 16, 17, 18, and 19 are diagrams showing the forms of the cams used to actuate the shuttle and needle-bar, and also how they are timed with respect to each other to effect the required result, all as will be fully explained 10 below. Fig. 20 is a plan, showing the parts of my invention in place except the throat-plate, this being removed in order that the position of the parts below it may be the better understood.

15 The machine shown in the drawings is a common form of a wax-thread sewing-machine with my improvements applied to it. The needle *c* is a hooked needle mounted in the needle-bar *E*, which reciprocates in a vertical groove in the horizontal slide *G*, and this slide is mounted in ways *H H*, *H' H''*, all in the usual way, except that I prefer to put one pair of ways, *H' H''*, on one side of the slide *G*, and the other pair, *H H*, on the other side. 20 25 This slide *G* is reciprocated by means of a bell-crank lever, one arm of which is connected, by means of a pin, *p*, to a cam-slot in the wheel *L*, while the other arm, *N*, is connected, by a pin, *n*, to a straight slot in a piece attached to the slide in the proper manner, all 30 in the usual way. The purpose of this slide *G* is of course to feed the material to be sewed, and in Figs. 13, 14, and 15 is shown one of many known means for regulating the length 35 of stitch. The pin *n* is adjustable in a slot in arm *N*, and it slides in a slot in a block, *n'*, attached to the slide *G*.

The needle-bar *E* is fast to the slotted piece *F*, and receives its motion from this piece *F*, 40 which is moved by the pin *l*, and this pin *l* is fast to a lever, *J*, which lever is actuated by the pin *m* on the wheel *L*, all in the usual way, except that I have formed a slot in the lever *J*, so shaped, in view of the revolution of 45 the pin *m*, as to give the desired motions to the needle. (See Figs. 16, 17, 18, and 19.)

The shuttle-driver *D* is actuated by a bell-crank lever, which, for convenience, is pivoted to a stud on the upper wall of the machine. 50 One arm of the bell-crank lever *D*² is connected to a cam, *D*³, on the main shaft, which cam is so shaped (see Figs. 16, 17, 18, and 19) as to give the desired motions to the driver, and the other arm, *D'*, is pivoted to a link, *k'*, which 55 is pivoted to the shuttle-driver *D* by the screw *k*, as illustrated by Figs. 11 and 12 of the drawings, and shown with the other parts in Fig. 20.

The shuttle *C* is provided with a needle-point, *a*, (which I prefer to secure by a set-screw, as 60 shown in Figs. 5 and 6,) in order that it may more readily enter the loop of the needle-thread before it is spread. It has tongues projecting from each side and from its front end, adapted to enter grooves in the shuttle-race, 65 as shown in Figs. 5, 6, 7, 8, and 9. Its nose is V-shaped, and a wire bow, *q*, extends on the under side from its nose to its butt.

The race consists of four parts, *A A'* and *B B'*, which are grooved to receive the tongues of the shuttle, and arranged as shown in the drawings. The parts *B B'* are pivoted to the frame, and are held with their pointed ends near each other by the spring *i*, which is prevented from drawing these ends too near together by the stops *h h*.

The shuttle-driver *D* has two arms, which lie above the race, and it is held in the race by tongues, which project from each side of its rear part and enter the grooves in the race.

The pin *b*, mounted in the lever *P*, may be 80 called a "cast-off," as its function is to free the loop from the hook on the needle. The lever *P*, which carries it, is pivoted to the slide *G*, and is pulled in one direction by the spring *f*. This spring *f* forces the lever *P* against the stop *e* when the needle is in the fabric, as shown in Figs. 2, 3, and 4, so that when the slide *G* is moved to feed the fabric the fulcrum of the lever *P* is carried forward or away from the stop *e*, (that fulcrum being 90 fast to slide *G*,) and the pin *b*, thus pressed against the back side of the needle *c* by the spring *f* for the stop *e*, is all that prevents the lever *P* and its pin *b* from being pulled forward by spring *f* until the pin *b* rests against 95 the needle; and as the fulcrum of the lever *P* is carried back to the left in Fig. 3, the lever *P* moves on its fulcrum until the pin *b* rests against the back of the needle. When the needle *c* descends low enough the pin *b* is 100 pulled over its point by the spring *f*, but prevented from going too far by the lever *P* striking the stop *d*, fast to the slide *G*.

The frame is marked *x* and the throat-plate *g*.

I have not shown in the drawings the overhanging arm or its attachments, as my present invention does not relate to those parts. All that is necessary to make a practical working machine embodying my invention is to attach to the machine shown in the drawings the ordinary overhanging arm and its appliances in common use in hooked-needle sewing-machines of this kind, adapting to it any of the well-known take-ups in use in the common shuttle sewing-machine.

Operation: As the machine starts, the awl descends and makes a hole for the needle to rise through. As the awl rises, the needle passes up through the hole made by the awl, the thread is placed in the hook of the needle 120 by the looper, the needle is moved sidewise horizontally away from the operator, who sits facing the side of the machine, with the fly-wheel on his right hand. There is the usual slot in the throat-plate to allow this sidewise 125 motion, and the amount of this sidewise motion is equal to the desired length of stitch. When the needle has moved sidewise far enough to make the desired length of stitch, and the needle-thread has been placed in its 130 hook, it descends. During its descent, and as soon as it has got so low that its point is below the nose of the shuttle, the shuttle receives a slight forward motion, which carries its

point into the loop of the needle-thread. After the needle is at, or nearly at, its lowest point, the shuttle receives a second forward motion, while the loop is still held by the needle, and is carried by this second forward motion far enough forward to cause its nose to enter the loop. These two motions of the shuttle may be one; but it is desirable to have two with a rest between. After the shuttle-nose is well 5 into the loop the needle receives a slight upward motion, to remove the loop from its hook. This removing the loop is accomplished as follows: During the descent of the needle the cast-off pin *b* is pressed, by the spring *f*, against 10 the back side of the needle, as described above, so that when the needle descends low enough the pin is drawn forward by the spring over the point of the needle and against the loop. This slight upward motion of the needle then 15 takes place, and as the loop is prevented from rising by the pin *b* it is pulled out of the hook in the needle. As soon as the needle completes this slight upward motion the shuttle is moved forward rapidly, spreading the loop, 20 and carrying the loop over the inclined ends of the movable parts *B B'* of the race, and opening these movable parts, the tongues on each side of the nose of the shuttle entering the grooves in these parts *B B'*, and making it practically impossible for the loop of the needle-thread 25 to be carried forward by the shuttle. By this last motion the shuttle is carried as far forward as it can go. These motions of the shuttle are all imparted to it, of course, by the shuttle-driver, which is in contact with the 30 butt of the shuttle, and when the shuttle has thus completed its forward motion the driver receives a slight backward motion, just sufficient to move the driver far enough from the 35 butt of the shuttle to allow the needle-thread to pass freely between them. The needle, after completing this slight upward motion, dwells a little in that position, so as to make 40 sure of the loop being drawn out of its hook, and then descends again, and moves sidewise under the pin *b*. As this sidewise motion of the needle is caused by the motion of the slide *G*, the lever *P* is also moved sidewise at the 45 same time, so that it strikes the stop *e*, and its upper end, carrying the pin *b*, is therefore moved 50 in a contrary direction over the needle, so that the needle and pin *b* are brought into the proper relative position for the next stitch. The needle-thread is drawn up off the slanting 55 ends of the movable parts of the race, passing between these ends and the forward ends of the stationary race, and between the driver and the butt of the shuttle, and is tightened to form the stitch in any usual way. 60 It will be clear from the above description that the movable parts *B B'* of the race are not essential for preventing the loop of needle-thread from being pushed forward by the shuttle when a hooked needle is used, for the reason that the hooked needle holds the thread 65 until it is released by the cast-off; but if these movable parts be dispensed with the cast-off

pin *b* must be brought close up under the shuttle, and the upward motion of the needle, after the loop is in contact with the cast-off pin, 70 must be so regulated that it will slacken the loop sufficiently to allow the shuttle to pass through, and yet not bring its hook above the cast-off pin until the shuttle has got nearly or quite through. If the needle does not slacken 75 the thread sufficiently, the shuttle must be made to open the loop, as in the ordinary shuttle machine. This is an important feature of my invention, and its principle consists in the use of the pin in such relation to the hooked needle 80 that the loop of needle-thread will be brought upon one side of the pin and the needle on the other with its hook toward the pin, in order that when the mouth of the hook is above the level of the pin the thread will be 85 readily disengaged from the hook. I have shown and described mechanism which I believe to be the best mode, on the whole, of applying that principle; but I have contemplated applying it by attaching the cast-off pin to 90 some other moving part than the feed-slide, and also by using a stationary cast-off pin, and so altering the cam-groove in the face of the wheel *L* and in the lever *J* as to carry the point of the needle under the stationary cast-off pin, elevate the needle sufficiently to bring its hook above the level of the pin, retract the needle, and move it back again sidewise into position for its ascent. All that is necessary 95 is to give such a motion either to the needle 100 alone, or to the needle and also to the cast-off pin, that the loop of the thread, while in the hook of the needle, shall be brought on one side of the cast-off pin and the needle on the other side, with the mouth of its hook next the 105 pin and elevated sufficiently to allow the thread to be drawn out.

The parts *B B'* prevent the loop of needle-thread from being drawn forward by the shuttle, and make it unnecessary to rely upon the 110 hook of the needle to hold it.

The shape of the cam for actuating the shuttle will be understood by reference to the diagrams in Figs. 16, 17, 18, and 19. In the upper part of each of these figures is shown 115 one position of the pin *m* on the wheel *L* and the corresponding position of the lever *J*. In the lower part of each figure is shown the position of the roll *D⁴* on the arm *D²* of the bell-crank lever which operates the shuttle-driver, 120 when the pin *m* is in the position shown in the upper part of the same figure.

What I claim as my invention is—

1. The combination of the shuttle *C* with the hooked needle *c* and the lever carrying the 125 cast-off pin *b*, and their actuating mechanism, substantially as described.

2. The combination of the strippers *B B'*, pivoted and provided with the spring *i* and the shuttle *C*, with the hooked needle *c* and the 130 lever carrying the cast-off pin *b* and their actuating mechanism, substantially as described.

3. The combination of the hooked needle *c*, lever *P*, provided with the cast-off pin *b* and

spring *f*, with the feed-slide *G*, provided with stops *d* and *e*, substantially as described.

4. The shuttle-race above described, consisting of the stationary parts *A A'* and the parts *B B'*, provided with spring *i*, one end of each of the parts *B B'* being pivoted, the other ends being adapted to be separated from each other by the shuttle in its forward motion, all substantially as set forth.

10. 5. A sewing-machine shuttle provided with side bearings, whereby it is adapted to be supported on each side by the shuttle-race, and having its point midway between these bearings, substantially as described.

15. 6. In combination, the double raceway *A A' B B'* and the shuttle *C*, supported on both sides by the race, with its point *a* midway between the walls of the race, substantially as described.

20. 7. In combination, the hooked needle *c*, shuttle *C*, and race *A A' B B'*, the race supporting the shuttle on both sides, and the needle and the point of the shuttle adapted to move midway between the walls of the race, substantially as described.

25. 8. The shuttle-driver *D*, provided with bearings by which it is adapted to be supported

and moved in the race, and with two side arms adapted to receive the shuttle between them, its main portion adapted to act on the butt of 30 the shuttle, and its arms adapted to act on each side of the shuttle-nose, all substantially as described.

9. In combination, the shuttle *C*, its driver *D*, and the race *A A' B B'*, the shuttle having 35 its point *a* midway between the walls of the race, and both shuttle and driver supported by and moving in the race, all substantially as described.

10. In a shuttle sewing-machine, the combination, with the shuttle, having side bearings, and its driver, also having side bearings, of a race supporting both the driver and shuttle, the side bearings of both engaging with the same race, substantially as described. 40

11. The combination of the needle-bar *E*, the bar *F*, the feed-slide *G*, the cam-slotted lever *J*, provided with the pin *l*, the crank-disk provided with the pin *m*, and shaft *k*, substantially as described. 45
